UNITED STATES PATENT OFFICE.

MARK A. PENNEY, OF PERRIS, CALIFORNIA.

BRAKE-SHOE.

SPECIFICATION forming part of Letters Patent No. 471,891, dated March 29, 1892.

Application filed November 19, 1891. Serial No. 412,406. (No model.)

To all whom it may concern:

Be it known that I, MARK A. PENNEY, of Perris, in the county of San Diego and State of California, have invented a new and Improved Shoe for Wagon-Brakes, of which the following is a specification, reference being had to the annexed drawings, forming a part thereof, in which—

Figure 1 is a longitudinal section of my improved brake-shoe. Fig. 2 is a rear view, and Fig. 3 is a face view.

Similar letters of reference indicate corresponding parts in all the views.

The object of my invention is to provide a brake-shoe for road-wagons, having a face which may be readily renewed.

My invention consists in a brake-shoe body formed of cast-iron or other suitable material and provided in the face thereof with a recess 20 for receiving blocks of wood or other material to form the frictional face of the brake, all as will be hereinafter more fully described.

The brake-shoe body A is formed of a curved casting conforming to the curvature 25 of the rim of the wheel to which the brake is to be applied. The back of the casting is provided with an arm a for attachment to the brake-bar b. In the face of the casting is formed a recess c, which extends from the upper end thereof to a ledge d at the lower end, and the side walls of the recess are furnished with inwardly-projecting flanges e, having sufficient width to retain in the recess the blocks B, used for the friction-surface or

brake. The said blocks B are preferably 35 made of hard wood; but they may be made of metal, rawhide, or other material suited to the purpose. The lower block rests upon the ledge d, and a rod or bolt f, passing transversely through the upper end of the shoe-body A, retains the block in the recess c. The arm a is secured to the brake-bar b by means of bolts, and the said bar, when the brake is applied, presses against the shoulder g, formed on the shoe-body. The flanges e, 45 formed on the shoe-body, are beveled and rounded on their inner edges to facilitate the application of the shoe to the wheel-rim.

When the blocks B are worn so as to become unserviceable, they may be removed 50 from the body A and replaced by a new one after withdrawing the rod f.

Having thus described my invention, I claim as new and desire to secure by Letters Patent—

A brake-shoe holder A, formed of a single casting and having on its inner face at opposite edges thereof integral inwardly-projecting flanges e, stop-ledge d, and an external attaching-flange, the upper end of the recess c, 60 formed by the flanges e, being open to receive and permit the removal of the brake-blocks, substantially as set forth.

MARK A. PENNEY.
